FLEXIBLE PLASTIC BRASSIÈRE OR THE LIKE

Joseph Condé, New York, N. Y.

Application April 11, 1952, Serial No. 19,291

Term of patent 14 years

(Cl. D20—4)

To all whom it may concern:

Be it known that I, Joseph Condé, a citizen of the United States, residing in New York city, county and State of New York, have invented a new, original, and ornamental design for a Flexible Plastic Brassière or the like, of which the following is a specification, reference being had to the accompanying drawing, forming part thereof:

Figure 1 is a front view of a flexible plastic brassière or the like showing my new design;

Figure 2 is a side elevation of the same; and

Figure 3 is a fragmentary longitudinal sectional view taken on line 3—3 of Fig. 1.

The dominant feature of the design resides in the elements shown in full lines.

I claim:

The ornamental design for a flexible plastic brassière or the like, as shown and described.

JOSEPH CONDÉ.
